LABORATORY TABLE FOR RESEARCH WORK
IN HOSPITALS AND THE LIKEÅke Lars Fredrik Jacobsson, 1A Viktor Rydbergsgatan,
Gothenburg, Sweden
Filed Nov. 9, 1961, Ser. No. 151,316

1 Claim. (Cl. 108—13)

The present invention relates to wall tables for laboratories in hospitals and similar institutions. There is a need for such tables in certain instances because of the expanding research at the present time, where change of locales and lines of research very often lead to costly rearrangements in the locales as well as new installations in old and new laboratory rooms.

It is an object of this invention to provide a lengthy table having means to be secured in position along the wall of a room, and capable of being changed and adjusted to suit the development of work in a laboratory room.

It is a further object of this invention to provide a lengthy table having means to be secured in position along a room wall, and which will raise no difficulties on moving to new locales and no damage to the old locales, so that both locales will be promptly ready for their intended new use.

It is another object of this invention to provide a lengthy table having means to be secured in position along a room wall, and which has a design which will essentially facilitate a change of the breadth of the table in the cross direction of the wall.

A further object of this invention is to provide a lengthy table having means to be secured in position along a room wall, and in which a level of a portion of the table is capable of being changed with respect to another portion thereof.

With these and other objects in view the invention essentially consists in that the table, being a combination of at least two lengthy tables positioned side by side in front of each other along a room wall, has two table plates, preferably of different breadth, each carried at the necessary supporting places by a cross directed bracket, these brackets being separate brackets extending substantially along the whole breadth of its corresponding table plate, the inner bracket adjacent to the wall being arranged to be connected at its inner end to a wall connection and at its outer end to an outer freestanding pillar, the outer bracket being connected solely to said pillar, the connection consisting of coupling parts so designed that the coupling part of the outer bracket is similar to at least the inner end coupling part of the inner bracket, so that the preferably broader outer table plate will be able to replace from its normal outer position both of the two normally assembled table plates by coupling the outer bracket directly to the wall connection, or allow the inner, preferably narrower, table plate to remain as a sole plate for the table, the two coupling parts of the coupling having a continuous adjustment relative to each other in the vertical direction permitting the table plates to obtain arbitrary level positions.

In the drawing:

FIGURE 1 is a side elevational view of the table,

FIGURE 2 a plan view thereof, and

FIGURE 3 is a side view of the table on a smaller scale.

The laboratory table consists in the embodiment shown of two lengthy table plates A and B, preferably of different breadth, lying with their long edges side by side in front of each other and of the wall 3. Each table plate is supported by brackets 1 and 2 at places where the supporting is deemed necessary, the brackets being in line

2

with each other and cross-directed against the length direction of the table and of the wall. These brackets are detachably coupled to each other, preferably by means of a between part, and the inner bracket 2 next to the wall is detachably coupled to a wall connection which has the shape of a coupling part 4. The between part between the brackets and the outer bracket has its common coupling in the form of the coupling between the wall and the inner end of the inner bracket, permitting the outer bracket with its preferably broader table plate to be directly connected with the wall coupling part, when the inner bracket is removed.

The brackets as shown are made of iron or other metal sheets bent in a U-shape with the long U-opening turned upwards. The breadth of the brackets in the vertical direction preferably increases towards their coupling end or ends.

The inner bracket 2 is carried at one end by the wall coupling part 4 and at the other end by a pillar 5 serving as a between part between the two brackets. The wall coupling part consists of a vertical bar with a C-profile in cross section, said bar, fastened on the floor, being attached to the wall in a suitable detachable way. The outer pillar 5 for the inner bracket 2 consists of two vertical C-profiled bars 5a, 5b similar to the vertical wall bar and welded together with their backs against each other, said pillar being adjustable in the vertical direction by means of a foot screw 6. The C-bar 4 of the wall constitutes the one coupling part for the connection of the inner bracket 2, and the outer C-bar 5a of the pillar constitutes the one coupling part for the connection of the outer bracket 1. The opposing end of each bracket has a T-head 7a as a corresponding coupling part suited to grip into the C-bar, said T-head being provided with a leg 7b welded within the U-bracket between its two side walls along the upper lengthy opening 8 between them. The leg in side view has the shape of a lengthy lying Z causing the T-head to have a lowered position beneath the upper edge of the bracket, as shown in FIGURE 1. A locking bolt 9 in the oblique direction is screwed through the bottom of the bracket with a bolt head 9a serving as a grip for the turning of the locking bolt. This bolt is positioned in such a way that the end of the same, screwed through the head, will abut against the inner surface of the back of the C-bar and force the T-head strongly against the inner surface of the forward wall of the C-bar.

The brackets have a larger breadth in vertical direction near their supported ends. This end of each bracket has an upper portion cut away, as shown in the drawing, giving the lower portion the shape of a protruding nose 1a, 2a, 2'a which enters through the vertical lengthy opening of the corresponding C-bar to bear against the inner back surface of the C-bar. The inner bracket 2 may, if desired, have an arbitrary connection with the pillar, but in the preferred embodiment the connection also consists of a coupling similar to the one on the wall. This has a certain advantage not only in the manufacturing but also in that it will be convenient to have between-lying brackets with like ends which will facilitate the mounting as well as a building up of more than two table plates side by side to increase the total breadth of the table if desired.

By the locking bolt the bracket is steadily maintained at its C-bar independent of its mounted position above the floor. Said position may be arbitrarily chosen along the C-bar. The load on the bracket will help to maintain the bracket in position as the load pressure causes a pressing of the bracket nose against the inner surface of the back of the C-bar and increases the pressure of

the T-head against the opposing surface of the C-bar. As will be apparent, the device will permit three different table breadths to be used, viz a table plate on the inner bracket alone, a table plate with the outer bracket alone replacing the inner bracket with its table plate, as well as the two brackets with their table plates in assembled use, as shown in the drawing.

The table plates are detachably connected to the brackets, for instance by screws 10 pressing against flat iron tongues 11 from the table plates directed downwardly between the walls of the bracket. As the coupling design permits the brackets to be positioned on different heights the inner table plate may, for instance, be positioned higher than the outer table plate, with a vertical wall strip between them as a holder for electric bulbs, gas taps and the like. The one coupling part is 15 slideable in the other.

The inner vertical C-bar 4 and the outer pillar 5 may be free standing on the floor or detachably secured to the same.

What I claim is:

A laboratory table for research work in hospitals and the like consisting of an assembling of at least two lengthy table plates preferably of different breadth to be disposed side by side in front of each other along the wall of the laboratory room, the table plates being at each necessary support place supported by a cross-directed bracket for each of them, the two brackets being 20 executed as separate brackets carried by supports and stretching themselves in line with each other essentially along the whole breadth of the corresponding table plate, the inner bracket next to the wall being coupled with

its one end to a wall connection and with its other outer end to a pillar or the like standing on the floor, the outer bracket being coupled solely to said pillar, the coupling part of the outer bracket being alike the coupling part 25 at the inner end of the inner bracket, permitting the outer bracket to be directly coupled to the wall connection when the inner bracket is removed, enabling the use of a laboratory table of three different breadths, viz the two table plates assembled, the inner table plate alone, and the outer table plate alone replacing the inner table plate, the couplings being built up by coupling parts having a continuous adjustment path relatively each other in the vertical direction permitting the table plates to obtain arbitrary level positions, the one coupling part for each bracket consisting of a separate vertical C-profiled bar, and the other coupling part of a T-member protruding from the bracket end, the T-head thereof positioned within the T-bar and the leg thereof extending out through the lengthy opening of the C-bar, a locking 30 screw belonging to the T-member being in inclined position screwed through the T-head to abut against the inner surface of the back wall of the C-bar causing the T-head to be clamped against the inner surface of the forward wall of the C-bar.
